[57] CLAIM

The ornamental design for a filter for a household aquarium, as shown and described.

DESCRIPTION

FIG. 1 is a perspective view of a filter for a household aquarium embodying my new design;

FIG. 2 is a front elevational view thereof;

FIG. 3 is a rear elevational view thereof;

FIG. 4 is a top plan view thereof;

FIG. 5 is a left side elevational view thereof;

FIG. 6 is a right side elevational view thereof;

FIG. 7 is a bottom plan view thereof;

FIG. 8 is a vertical cross-sectional view thereof, taken along line 8—8 of FIG. 4;

FIG. 9 is a vertical cross-sectional view thereof, taken along line 9—9 of FIG. 4;

FIG. 10 is a vertical cross-sectional thereof, taken along line 10—10 of FIG. 4; and,

FIG. 11 is a reduced perspective view thereof, the broken-line showing of the aquarium tank and attachments being for illustrative purposes only and forming no part of the claimed design.
